V. Smith

United States Patent Office.

VINZENZ SMITH, OF MIDDLEBURY, OHIO.

Letters Patent No. 80,840, dated August 11, 1868.

IMPROVED SCREW-CUTTING MACHINE.

The Schedule referred to in these Letters Patent and making part of the same.

TO ALL WHOM IT MAY CONCERN:

Be it known that I, VINZENZ SMITH, of Middlebury, in the county of Summit, and State of Ohio, have invented certain new and useful Improvements in Screw-Cutting Machines; and I do hereby declare that the following is a full and complete description of the same, reference being had to the accompanying drawings, making a part of this specification, in which—

Figure 1 is a side view of the machine.

Figure 2 is a view of the top.

Figures 3 and 4, detached sections.

Like letters of reference refer to like parts in the several views.

In fig. 1, A represents a bed, on which are erected the standards B B'. In said standards is fitted a hollow shaft, C, having a thread cut upon its outer end, which is screwed into the standard B', whereas the opposite end is fitted so as to work freely in the standard B. D is a hand-wheel, whereby said shaft C is turned, for a purpose hereafter shown.

In the hollow of the shaft C is loosely fitted a shaft, indicated by the dotted lines a. To the inner end of this shaft is fitted, and secured, by means of the screws b, a socket, F. On the inner end of said socket is a screw-plate, G, fig. 3, in which are fitted the dies H for cutting the thread on bolts. I, fig. 1, is an adjustable standard, secured to the base or bed by a bolt, C, fitted to and working in a slot cut in the bed for that purpose. To this adjustable standard is attached a stay, J, in which is fitted a pair of blank-dies, K, fig. 4.

The practical operation of this machine is as follows:

The bolt to be cut is inserted in the blank-dies K, and therein secured by screwing the dies together by the set-screws K', as shown in figs. 1 and 2, in which A' represents said bolt. The end of the bolt is then inserted in the screw-dies H, and a thread thereon cut by turning said dies by means of the crank B'. As the dies are being turned, the bolt is fed to them by the adjustable standard being drawn forward toward them, it being loosely fitted and secured to the bed. In order to cut the nut for the bolt, the screw-dies H are removed, and replaced by blank ones. In said blank-dies the tap is held, whereas the nut is held in the dies K, as was the bolt. The tap is now inserted in the nut, and the thread cut therein by turning the shaft and socket, as before, for the bolt, the nut being fed to the tap by the moving forward of the standard, in which it is secured.

By this apparatus, bolts and nuts are readily and easily cut, requiring no extra machinery for that purpose, the ordinary hand-drill, in common use in blacksmith-shops, being thus readily converted into a screw-cutting machine, by simply attaching the socket F to the drill-shaft of the machine, and attaching the stay J and dies to the standard, which latter may be allowed to remain attached to the standard as a permanent fixture, as it will not be in the way when using the machine for drilling.

The combination of mechanism herein described, for cutting screw-threads on bolts, nuts, &c., I do not claim; but

What I do claim is—

Modifying the structure of the parts of said combination, and combining with said combination the several devices, in virtue of which the apparatus may be used as a drilling-machine, as well as a bolt and nut-threading machine, all substantially as described and shown.

VINZENZ SMITH.
